TOY RAILROAD SIGNALS

Joseph L. Bonanno, South Orange, N.J., assignor to The Lionel Corporation, New York, N.Y., a corporation of New York

Application October 10, 1955, Serial No. 539,506

5 Claims. (Cl. 340—49)

The present invention relates to toy railroad signals and is more particularly directed toward signals of the banjo type adapted for use in connection with toy railroads.

The present invention contemplates a banjo type signal having swinging arm operated by a small electric motor and arranged to display or cover a signal lamp and to be operated to alternately cover and display the lamp so as to give a flashing signal resembling the signal given by the banjo signals used in the operation of full sized railroads.

The present invention further contemplates signal structure for the purposes made out of a small number of inexpensive parts and wherein the motor is one which requires a very small input of energy to actuate the swinging arm. The signal is characterized by the absence of complicated gear mechanism to effect the swinging of the arm from the rotor of the motor.

The accompanying drawings show, for purposes of illustrating the present invention, one embodiment in which the invention may take form, it being understood that the drawings are illustrative of the invention, rather than limiting the same.

In the accompanying drawings:

Figure 1 is a perspective view of the assembled signal; Figure 2 is an exploded perspective view of the signal;

Figure 3 is a side elevational view of the signal with parts in section on the line 3—3 of Figure 4, to show interior construction;

Figure 4 is a sectional view taken on the broken line 4—4 of Figure 3;

Figure 5 is a horizontal sectional view on the line 5—5 of Figure 3;

Figures 6 and 7 are front and side elevational views of the elastomeric washer employed to actuate the rotor; and

Figure 8 is a wiring diagram.

The signal employs a relatively heavy metal base 10 which carries a tubular column 11. The base carries insulated and grounded terminals (not shown) for connecting the signal to extraneous wiring. At the top of the column 11 is a head or frame 12 in the form of a non-magnetizable die casting. This frame has a forwardly opening recess indicated at 13 in which is mounted an insulated terminal 14 connected to a wire 15 which extends down through the column 11.

Above the lamp box forming recess 13 the frame 12 carries a laterally extending bracket 16 which terminates above and to the left of the left end of the lamp box, as is apparent from the drawings. The frame member 12 also has a downwardly extending portion 17 below the bracket. The extension 17 is connected with the lamp box by a cross member 18 and a brace 19 extends upwardly from the top of the lamp box.

A cover member 20 which may be made of insulating material as shown fits over the opening of the recess 13. It carries a contact member or lamp terminal 21 made of sheet metal and shaped to receive the base 22

2

of a lamp 23 whose bulb is indicated at 24. The contact member or terminal 21 has notches 25 to cooperate with the pins 26 carried by the lamp base and sharp, paint scratching members 27 which scratch away enough paint on the inside of the lamp box or recess to assure satisfactory grounding of the terminal 21.

The cover has flanges 28 which fit inside the walls of the lamp box-forming recess and accurately position the cover with respect to the frame or body 12. The cover 10 has a window, indicated at 29 opposite the lamp bulb. When the lamp is in position its center terminal 30 bears against the spring contact to complete the circuit for the lamp.

The motor mounting 17 supports a vibrating type 15 motor indicated generally at M. This motor has a coil 31 wound about a magnetizable core 32. This core carries insulating end members 33 and 34 forming a spool, and is secured in place by a screw 35 threaded into it from the rear of the motor mounting 17. This screw 20 passes through a magnetizable cup 36 and orienting washer 37 so that the spool and the magnetizable cup may be securely held in place.

The outer or front end of the spool carries a washer 38 made of elastomeric material and provided with a 25 series of outwardly extending, tangentially leaning, oblique fingers 39. The core 32 is drilled as indicated to receive a rotor shaft 40, preferably made of bronze, and this shaft carries a cup shaped magnetizable rotor 41 which extends back about the coil and in close proximity to 30 the rear cup 36.

One end of the winding 31 is grounded and the other end connected by a wire 42 with the terminal strip 14. The rotor 41 carries a crank pin 43 adapted to enter the slot 44 of an arm 45 pivoted on a screw 46 threaded 35 into the frame member 12 at 47.

When low voltage current is supplied to the circuit, the lamp is lighted and the coil 31 energized. The alternating current flux set up in the magnetic circuit, including the core 32 and cups 36 and 41 causes the rotor 40 41 to vibrate back and forth, guided and supported by the shaft 40. This vibration effects an alternate compression and release of the fingers 39 on the member 38 and, as these fingers are shaped in the manner stated, the fingers will impart a turning movement to the rotor 45 41, causing it to revolve in the direction determined by the sloping of the fingers. Here the rotor 41 revolves in a clockwise direction, as indicated in Figure 3. As the rotor revolves it will cause the arm 45 to swing back and forth between the full line and dotted line positions of 50 Figure 3 so as to cover and uncover the window and display and signal light or cut it off.

This operation takes place as long as current is supplied to the signal. It can be automatically set into operation by the passage of the train over a selected portion 55 of the track, or by a manual switch, if desired.

Since it is obvious that the invention may be embodied in other forms and constructions within the scope of the claims, I wish it to be understood that the particular form shown is but one of these forms, and, various 60 modifications and changes being possible, I do not otherwise limit myself in any way with respect thereto.

What is claimed is:

1. In combination, a support, a motor secured to the support and comprising a magnet coil having a horizontal 65 axis, a magnetizable core, a pole piece carried at one end of the coil having outwardly extending elastomeric, tangentially leaning, oblique fingers, and a magnetizable member rotatably carried by the core and having a wall bearing against the fingers, a lamp box carried by the support, a lamp in the box, the box having a window opposite the lamp, and an oscillating arm pivoted to the support and having an elongated slot, a pin on said

magnetizable member confined in said slot, the free end of the arm being shiftable by the motor between positions where it covers or uncovers the window.

2. A toy railroad signal comprising a metal base, an upwardly extending metal column, a metal head carried at the top of the column, the head having a lamp box provided with a forwardly opening window, a lamp in the lamp box, the head having a bracket arm above the lamp box and extending laterally beyond the window, a motor secured to the head under the outer end of the bracket arm and having a rotor turning on a horizontal axis, and a swinging arm pivoted to the bracket arm above the motor and drivingly connected with the rotor to oscillate back and forth, once for each turn of the rotor, the lower end of the swinging arm being moved to cover and uncover the window.

3. A trackside signal for toy railroads comprising a metal base, an upwardly extending metal column, a metal head carried by the column, the head having a lamp receiving recess, an insulated lamp socket terminal mounted in the recess, a recess cover having a second lamp socket terminal, a lamp bulb carried in one of the terminals and bearing against the other when the cover is in place, the cover having a window opposite the lamp bulb, the head having a bracket above the lamp box and lateral of the window and a motor mounting below the bracket, an arm pivoted on the bracket and having one end movable between positions where it covers and uncovers the window, and a motor secured to the motor mounting and having a rotor with a horizontal axis, and an eccentric connection with the arm to swing it back and forth.

4. A signal comprising a base, a vertically elongated supporting member mounted on said base, a signal light mounted on the upper end of said supporting member, an

4

arm extending outwardly from said supporting member above said signal light, a signal arm member pivotally mounted on the end of said arm, said signal member having an elongated slot defined therein extending in a direction radially outwardly from said pivot, a motor secured to said arm below the pivotal location of said signal member and having a rotor turning on a substantially horizontal axis, said rotor including a pin extending into the slot of said signal member to oscillate said signal member back and forth, said oscillation being such to bring said signal member to a position to cover said lamp at one end of its oscillation movement.

5. A signal according to claim 4 wherein said motor means includes a magnetizable core, resilient members extending outwardly from one end of said core, said members all being slanted in the same circumferential direction, and wherein said rotor includes a magnetizable member resting on said resilient members, and means to energize said magnetizable core whereby rotation of said rotor is effected as it is vibrated inwardly and outwardly on said resilient members.
